UNITED STATES PATENT OFFICE.

ADAM GEISEL, OF ST. LOUIS, MISSOURI.

CONCRETE BRIDGE.

SPECIFICATION forming part of Letters Patent No. 568,673, dated September 29, 1896.

Application filed March 23, 1896. Serial No. 584,439. (No model.)

To all whom it may concern:

Be it known that I, ADAM GEISEL, of the city of St. Louis, State of Missouri, have invented certain new and useful Improvements 5 in Concrete Bridges, of which the following is a full, clear, and exact description, reference being had to the accompanying drawings, forming a part hereof.

My invention relates to an improved concrete arch-bridge; and it consists in the novel 10 construction, combination, and arrangement of parts hereinafter described and claimed.

In the drawings, Figure 1 is a side elevation of my improved arch-bridge. Fig. 2 is 15 a longitudinal sectional view of the bridge shown in Fig. 1. Fig. 3 is a horizontal sectional view on the line 3 3 of Fig. 1. Fig. 4 is a vertical transverse sectional view on the line 4 4 of Fig. 1, the view being broken away 20 at approximately the center of the bridge. Fig. 5 is a vertical transverse sectional view on the line 5 5 of Fig. 1, the view being broken away at approximately the center of the bridge. Fig. 6 is an enlarged longitudinal 25 sectional detail of the arch used in my bridge.

Referring by numerals to the drawings, the water 1 of the river rests on the bed 2, between the banks 3 and 4. In each of the 30 banks 3 and 4 an excavation is made for the abutments 5 and 6 and the wing-walls 7, 8, 9, and 10 of the bridge. Piles 11 and 12 are sunk in these excavations until a solid foundation is reached. The upper ends of these piles are sawed off on a horizontal line about 35 one foot above the bottom of the excavation. The ground plan of the abutments and wing-walls is shown in Fig. 3, the piling being shown in dotted lines. After the piles have 40 been driven and sawed off the excavations are cleaned out to the virgin earth. A layer of concrete about one foot in thickness is then placed in the excavation and thoroughly rammed around the heads of the piles. Similar layers of concrete are placed one on top 45 of the other in the excavations until the abutments and wing-walls are of the desired height. Each layer is thoroughly sprinkled with water before another is added, in order to form a thorough bond between the layers. 50 When completed, the whole mass of each abutment and its wing-walls is a solid body of concrete. When the abutments and wing-

walls get above the surface of the ground, suitable false work is erected to mold said abutments and wing-walls into the desired 55 shape. After the concrete-work has been finished, the false work is left in position about three days, or until the concrete has become sufficiently hardened to stand.

On the facing-walls of the abutments 5 and 6 are surfaces 13 and 14, upon which the ends of the arch 15 are seated, the lines of said surfaces corresponding to the radial lines of the arch. The arch is in three pieces when the bridge is complete, and consists of the 65 two sides 15^a and 15^b and the keystone 15^c. The surfaces 13 and 14 are covered with tar-paper or other suitable substance to prevent the arch from forming a bond with the abutment. The side pieces 15^a and 15^b are each 70 constructed in five sections 15^d, 15^e, 15^f, 15^g, 15^h, 15ⁱ, 15^j, 15^k, 15^l, and 15^m.

In constructing the arch I work from each end toward the center. The end section is cast and before it has time to set the next 75 section is cast and a bond forms between them, and so on until the pieces 15^a and 15^b are complete. At the boundary-line between the second and third sections from the outer ends of the pieces 15^a and 15^b the arch is between thirty-five and forty per cent. thicker 80 than at the inner ends of said pieces and about ten per cent. thicker than at the outer ends. The inner ends of pieces 15^a and 15^b are covered with tar-paper or other suitable 85 material to prevent a bond with the keystone. The keystone 15^c is then cast in position. The center of the arch should be elevated slightly above a true center (about one inch to forty feet) in order that it may form 90 a true arc of a circle after the bridge is completed and settled. The false work used in casting the arch should be left in position about twenty days after the arch is closed or long enough to allow the concrete to set. 95

I omit the usual haunchings on top of the arch and in their place I insert concrete walls 16 in the form of right-angled triangles. The short side of the triangle rests against the vertical face of the abutment and the hypotenuse rests upon the upper surface of the arch, thus bringing the long side of the right angle in a horizontal plane for the purpose of forming ribs to support the superstructure 100

of the bridge. Similar walls 17 join with the wing-walls and the edges of the arch. There is no bond between the walls 16 and 17 and the arch. The space between these walls 5 is filled with clean clay and rammed solid, after which the sidewalks and road-bed are laid in the usual way.

The iron railing is embedded in the coping and parapets, which are cast of concrete and 10 integral with the walls 17. Several coats of plastering are applied to the face of the arch and the wing-walls, the finishing coat showing an imitation of alternate smooth and rock face stonework.

15 Aside from the process of construction and the details of composition used, the distinguishing features of my concrete arch-bridge are the joints in the arch and the substitution of the walls 16 and 17 for the usual 20 haunchings, thus leaving the pieces of the arch free to expand or contract without cracking or breaking the arch and will also allow a settlement of the support of the arch without cracking the arch.

25 I claim—
1. A concrete bridge consisting of abut-

ments, the haunches comprising voussoirs of concrete bonded together, said haunches being unbonded to the abutments and to each other, substantially as specified.

30 2. A concrete bridge consisting of abutments, haunches comprising voussoirs of concrete bonded together, said haunches being unbonded to the abutments, and a keystone, said keystone being unbonded to said 35 haunches, substantially as specified.

3. A concrete bridge consisting of abutments, the haunches comprising voussoirs of concrete bonded together, said haunches being unbonded to the abutments, a key- 40 stone, said keystone being unbonded to said haunches, and walls on top of said haunches, said walls being unbonded to said haunches and to said abutments, substantially as specified.

45 In testimony whereof I affix my signature in presence of two witnesses.

ADAM GEISEL.

Witnesses:

E. E. LONGAN,
MAUD GRIFFIN.
